UNITED STATES PATENT OFFICE.

PERCY E. HUNTER, OF PITTSBURGH, PENNSYLVANIA.

ANNEALING-BOX.

1,305,605.

Specification of Letters Patent. Patented June 3, 1919.

Application filed April 15, 1918. Serial No. 238,728.

To all whom it may concern:

Be it known that I, PERCY E. HUNTER, a citizen of the United States, residing at 5469 Stanton avenue, Pittsburgh, in the county of Allegheny and State of Pennsylvania, have invented certain new and useful Improvements in Annealing-Boxes, of which the following is a specification.

My invention consists of an improvement 10 in annealing boxes adapted for the usual uses of such devices, and is particularly intended for use in annealing sheet metal used in the manufacture of tin plate.

In the use of such boxes, they are subject 15 to the severe action of continuous heat at high temperatures, and especially to the cutting or deteriorating action of the flames of the annealing oven. These conditions result in rapid destruction of any abrupt projecting portions of the box which may happen to be in the path of the gases of combustion, for which reason it is desirable to maintain over the entire several surfaces of the box, as plane and unvarying contours as 20 possible, avoiding any shoulders or projections which might be weakened or cut away by action of the fire. It is especially important to avoid any such features in connection with the main joints of the metallic 25 members of which the box is made, and the present invention is designed to provide a construction in which these objections are avoided, while maintaining a maximum strength, resistance to deterioration, rigidity, and efficiency throughout the structure.

Generally stated, the improvement consists in providing the main body portion, *i. e.*, the sides and ends, of a continuous uninterrupted integral wall of uniform thickness, and a top portion connected therewith, in such a manner as to present a series of outer surfaces to the action of the oven heat, in the absence of any objectionable variations or projections.

The box is composed of two main blanks, one for the main side and end portions, and one for the top portion, as hereinafter described.

In the drawings, which show one preferred embodiment of the invention,

Figure 1 is a view in cross section of the side and end forming blank before welding to form the joint about midway of one of the sides or ends;

Fig. 2 is a similar view after welding;

Fig. 3 is a detail view showing a modified

arrangement, locating the welded joint adjacent to one of the corners, instead of at the middle of the side or end;

Fig. 4 is an enlarged view in vertical section and elevation, of the complete annealing box, indicated by the line IV-IV of Fig. 5;

Fig. 5 is a plan view of the complete box;

Fig. 6 is a sectional detail view of the 65 upper corner showing a riveted joint; and

Figs. 7, 8 and 9 are enlarged sectional detail views of the main wall, showing the steps of the welding operation in bringing the joint to finished shape.

In making the main body portion of the annealing box, I cut a blank of plate metal of suitable thickness and size so that when bent into form for use, it will approximate a rectangle having the back 2, ends 3, and the front composed of the end portions of the plate 4, 4, overlapping at 5, as shown in Fig. 1.

The overlap is of sufficient width, when these portions are adjusted, to insure ample 80 contacting area of the plates, for a good welded joint. In order to provide ample stock for spreading outwardly of the meeting ends in making the joint, the ends 3 are, in the process of manufacture, brought 85 inwardly a sufficient distance so that when the material is stretched in making the weld, the ends will assume a position at right angles to the sides, as shown in Fig. 2. Thus, when completed, the box will be of the form 90 shown in Fig. 2, composed of the back 2, ends 3, 3, and continuous integral front 4-4. The corners are preferably rounded, as shown, for good construction.

In welding the overlapping meeting ends 95 of the front portions 4, 4, they are brought together as in Fig. 7, and are then swaged down under a hammer, die, press, or other means, the meeting welded faces assuming a diagonal line *b* with the opposite corner portions of the overlapping ends gradually 100 merged into the general plane of the main front plate, inside and out, as at *c*, *c*, Fig. 8. The welding pressure is continued until the projecting portions are substantially 105 flattened into the planes of the inner and outer surfaces, as in Fig. 9, by which operation the welded joint is increased, the rectangular symmetry of the box is assumed, and the sides and ends are formed to compose 110 a continuous substantially rectangular piece of homogeneous metal.

It is not, of course, absolutely essential that the exact planes of the inner and outer surfaces be approximated throughout, except at the inner upper portion of the box, 5 for snug insertion of the top.

The top 6 is made of a single piece of pressed plate metal having a middle upwardly arching dome portion and a continuous downwardly turned flange 7. The top 10 is of a size to fit by its flange snugly within the upper edges 8 of the box, as in Fig. 4, when complete, and to insure a tight fit, is of a size to just admit insertion without excess clearance when the upper portion of the 15 box is expanded by heat, so that as it cools, it will shrink around the top. If preferred, the top may be flat.

Thereafter, the flange and box edges are welded together all around and the parts are 20 made practically integral.

If preferred, the flange 7^a of the top may be riveted to the sides 3^a, as indicated in Fig. 6, either with or without the welding operation, thereby insuring a solid substantial joint. The top may also be merely inserted, a described, and shrunk in, without either welding or riveting, and will thus be continuously held in place.

By either construction, and with one side 30 or end of the box welded in the manner described, I provide continuous, smooth, unobstructed surfaces at all points so that there is no opportunity for the flame of the annealing furnace to attack any projecting portion, thus preventing wasting or weakening at any such points.

By inserting the flange of the top 6 within the top edge portion of the box I avoid any outer projection, and present a smooth, 40 even surface, with ample reinforcement and strength. Also, by seating the top slightly below the top edge, as shown, I provide a surrounding crevice or gutter 9 or 9^a adapted to be filled with sand, clay, or other suitable packing material, as is commonly done, 45 for closing of leaks.

The box is provided with lifting lugs or buttons 10 at any suitable locations, preferably having shouldered and countersunk 50 riveted connection with the inner sides of the box, as indicated at 11, thus facilitating easy and cheap renewal of these parts, when broken or worn.

In making the welded joint 4^a it is preferably located at a position between the corners, either at the side or end of the box. It may be made at the middle as in Figs. 1 and 2, or at one side of the middle, as in Fig. 3. With either construction, I avoid 60 joining the side and end of the box at the corner, thereby preventing any weakening of the corner which thus maintains the original integral continuity of the plate. This is a feature of very considerable 65 advantage over prior constructions having

corner joints of various kinds, which are subject to the weakening or destructive effect of the heat or other influences or strains resulting in failure of the box at such points.

The construction, operation, advantages, 70 and utility of the invention will be readily understood and appreciated by those accustomed to the use of annealing boxes of this general class.

It is comparatively cheap and simple in 75 construction; durable and efficient in continued use because of the equal uniform construction throughout; and provides ample compensations for the usual strains and requirements of devices of this type. 80

What I claim is:—

1. An annealing box composed of a rectangular plate metal body portion formed of a continuous integral blank preliminarily formed with its ends slightly converging 85 whereby to provide overlapping ends at one side having ample metal for welding, said ends being welded together between the corners of the box with a resulting expansion and resumption of rectangular formation 90 of the sides and ends, and a top secured to the upper portion of the body portion.

2. An annealing box composed of a rectangular plate metal body portion formed of a continuous integral blank preliminarily 95 formed with its ends slightly converging whereby to provide overlapping ends at one side having ample metal for welding, said ends being welded together between the corners of the box with a resulting expansion 100 and resumption of rectangular formation of the sides and ends, and a continuously smooth construction at the welded joint, and a top secured within the upper portion of the body. 105

3. An annealing box composed of a rectangular plate metal body portion formed of a continuous integral blank preliminarily formed with its ends slightly converging whereby to provide overlapping ends at one side having ample metal for welding, said ends being welded together between the corners of the box with a resulting expansion and resumption of rectangular formation of the sides and ends, and a continuously 110 smooth construction at the welded joint with continuously smooth originally integral corners, and a top secured within the upper portion of the body. 115

4. An annealing box composed of a rectangular plate metal body portion formed of a continuous integral blank preliminarily formed with its ends slightly converging whereby to provide overlapping ends at one side having ample metal for welding, said 120 ends being welded together between the corners of the box with a resulting expansion and resumption of rectangular formation of the sides and ends, and a top provided with a downwardly extending flange in shrunk 125

engagement with the inner upper portion of the body.

5. An annealing box composed of a rectangular plate metal body portion formed of a continuous integral blank preliminarily formed with its ends slightly converging whereby to provide overlapping ends at one side having ample metal for welding, said ends being welded together between the corners of the box with a resulting expansion and resumption of rectangular formation of the sides and ends, and a top provided with a downwardly extending flange in shrunk engagement with the inner upper portion of the body and welded thereto.

6. An annealing box composed of a rectangular plate metal body portion formed of a continuous integral blank preliminarily formed with its ends slightly converging whereby to provide overlapping ends at one side having ample metal for welding, said ends being welded together between the corners of the box with a resulting expansion

and resumption of rectangular formation of the sides and ends, and a top provided with 25 a downwardly extending flange in shrunk engagement with the inner upper portion of the body and riveted thereto.

7. An annealing box composed of a continuous side and end wall body portion of 30 plate metal and an outwardly arching top connected therewith by an inwardly inserted flange and providing between the top and the upper edge of the box a continuous sand or clay holding gutter.

8. An annealing box composed of a rectangular plate metal body portion formed of a continuous integral blank having its ends overlapping and welded together and reduced to a substantially uniform thickness 40 between its ends, and a top connected therewith by an inwardly inserted flange providing an upper continuous V-shaped opening.

In testimony whereof I hereunto affix my signature.

PERCY E. HUNTER.
